Attorney.

UNITED STATES PATENT OFFICE

2,252,023

BOX

Ersel C. Mulnix, Chicago, Ill.

Original application December 12, 1936, Serial No. 115,551. Divided and this application March 7, 1938, Serial No. 194,240

4 Claims. (Cl. 229—41)

The invention relates to improvements in boxes and more especially in boxes made of flexible material such as boxboard, paper, or the like and has for its primary object the provision of a box construction of the character indicated made in two swinging parts and so constructed and arranged as to effect comparatively snug fitting between them, the present application being a division of my application filed in the Patent Office on December 12, 1936, Serial No. 115,551.

Other objects will appear hereinafter.

The invention consists in the combinations and arrangements of parts hereinafter described and claimed.

The invention will be best understood by reference to the accompanying drawing forming a part of this specification and in which

Fig. 1 is a perspective view of a foldable box embodying the invention;

Fig. 2 a plan view of the blank from which the box is formed;

Fig. 3 a partial perspective view showing the relative positions of the parts as the box is being closed; and

Fig. 4 an end view showing the box in closed condition.

The embodiment of the invention illustrated comprises an integral blank made of boxboard, paper or the like, having one interior portion 10 set off by scoring or creases as shown to constitute the top or cover portion of an outer box member. The top portion 10 is connected as indicated with a corresponding bottom portion 11 by a common wall member 12 which serves as a swinging connection between the outer and inner box members. The top portion 10 is provided with side walls 13 connected by triangular flaps 14 and 15 with the end wall 16. In assembling the box, the side walls 13 are first folded inwardly onto the top portion 10 and the end wall 16. The end wall 16 is provided with a securing flap 17 which is folded inwardly onto the flap 15 and secured to the wall 16 by means of a central staple or wire stitch as usual in this form of boxes and as will be readily understood by those skilled in this art.

The securing flap 17 thus constitutes an ordinary and well known form of securing flap co-operating with the corner flaps 14 and 15 for securing that end of the outer box member in distended form.

The end wall 16 is provided with a transverse slit 18 having downwardly and outwardly di-

verging ends 19 for reception of a handle member formed on the other end of the box blank.

The bottom portion 11 is provided with end walls 20 connected by triangular foldable flaps 21, 22 and 23 with the ends of the side walls 13 as best shown in Fig. 2. The adjacent corners of the side walls 13 are formed into locking tongues 25 as shown, said locking tongues being adapted and arranged to be inserted in diagonal slits 24 in the end walls 20 when the triangular flaps 21, 22 and 23 are properly folded for the purpose, thereby serving to secure this edge of each of the side walls 13 in place when the box is formed, as indicated in Fig. 1.

15 The walls 20 are connected as best indicated in Fig. 2 with the ends of the end wall 28 for the inner box member, by folding flaps 26 and 27 which serve the same function here as the flaps 14 and 15, but are cut off at their outer corners to facilitate the more complicated folding manipulation.

15 The walls 20 are connected as best indicated in Fig. 2 with the ends of the end wall 28 for the inner box member, by folding flaps 26 and 27 which serve the same function here as the flaps 14 and 15, but are cut off at their outer corners to facilitate the more complicated folding manipulation.

25 A handle flap 29 is formed at the top of the end wall 28 as shown. The central portions 30 of the wall 28 and flap 29 are properly freed and scored as shown so that they may be doubled upon each other to form a handle member insertable through the slot 18 when the box is closed as indicated in Fig. 1. Securing flap 31 is provided at each side at the top of wall 28 to serve as a means of securing the flaps 26 and 27 in distended form in the usual way.

30 So much of the box as has already been described is precisely the same as that disclosed in my said application, Serial No. 115,551 and requires no further description here.

It is to be noted however, that the scored lines 32 at the ends of the side walls 20, as best shown in Fig. 2, are inwardly inclined resulting in an inward inclination to the wall 28 to facilitate the 40 swinging of the wall 16 over the wall 28 and to cause a better fit of the parts when the box is made up into the condition shown in Fig. 1.

The better fit thus caused is best illustrated and indicated in Figs. 3 and 4 of the drawing. 45 Fig. 3 shows the positions of the parts during the closing of the box when the extreme free bottom edge of the swinging cover portion 10 is just about to pass over the free upper edge of the bottom portion 11 and it will be noted that the arrangement is such that the former edge swings in close proximity to, if not actually touching, the corresponding top edge of the bottom portion. Then as the wall 16 is forced further downwardly over the wall 28, the lower edge of the 50 wall 16 is brought into close contact or associa-

tion with the bottom of the wall 26 so as to leave little if any gap at the point 33 in Fig. 4, a result also due to the inward inclination of the wall 26. This inward inclination of the wall 26 should be made to approximate the arc or path on which the wall 16 of the cover portion swings in the closing operation, which will, of course, vary in different sizes and forms of boxes, as will be readily understood.

While I have illustrated and described the preferred form of construction for carrying the invention into effect, this is capable of variation and modification without departing from the spirit of the invention. I therefore do not wish to be limited to the precise details disclosed, but desire to avail myself of such variations and modifications as fall within the scope of the appended claims.

I claim:

1. A box comprising an outer and inner box member swingingly connected together to cause the outer member to swing over the inner member to close the box, said outer member being substantially the full height of and substantially enclosing said inner member, the side of the inner member opposite the swinging connection being inwardly inclined from its bottom to its top and the corresponding side of the outer member being substantially perpendicular to its top.

2. A box comprising an outer and inner box member swingingly connected together by a common wall to cause the outer member to swing over the inner member to close the box, said outer member being substantially the full height of and substantially enclosing said inner member,

5 the side of the inner member opposite the swinging connection being inwardly inclined from its bottom to its top, and the corresponding side of the outer member being substantially perpendicular to its top.

10 3. A box, comprising an outer member including a top and a front side, and an inner member including a bottom and front side, said top and bottom of said members being swingably connected together rearwardly of said sides to permit the swinging of the outer member over the inner member to close the box, said outer member being substantially the full height of and substantially enclosing said inner member when

15 the box is closed, the inner angular relation of said side of said inner member and said bottom being less than 90°, and the inner angular relation of said side of said outer member with said top being not less than 90°.

20 4. A box, comprising an outer member including a top and a front side, and an inner member including a bottom and a front side, a common wall swingably connecting said top and bottom together at the rear edges thereof to permit the swinging of the outer member over the inner member to close the box, said outer member being substantially the full height of and substantially enclosing said inner member when

25 the box is closed, the inner angular relation of said side of said inner member and its bottom being less than 90°, and the inner angular relation of said side of said outer member with its top being not less than 90°.

30 ERSEL C. MULNIX.
